DESIGN FOR A HANDBAG OR SIMILAR ARTICLE

Samuel R. Goldsmith, New York, N. Y.

Application January 9, 1937, Serial No. 66,971

Term of patent 3½ years

To all whom it may concern:

Be it known that Samuel R. Goldsmith, a citizen of the United States and resident of New York city, in the county of New York and State of New York, has invented a new, original, and ornamental Design for Handbags or Similar Articles, of which the following is a specification, reference being had to the accompanying drawing forming part thereof, in which,

Fig. 1 is a front elevational view of a handbag embodying my new design. Fig. 2 is an end elevational view thereof, and, Fig. 3 is a top plan view thereof showing the hand-strap in open position.

I claim:

The ornamental design for a handbag or similar article, substantially as shown and described.

SAMUEL R. GOLDSMITH.
